UNITED STATES PATENT OFFICE.

JAMES GOWANS, OF LEONIA, NEW JERSEY, ASSIGNOR TO SIDNEY BLUMENTHAL & CO., INC., OF NEW YORK, N. Y., A CORPORATION OF NEW YORK.

DESIGN FOR A TEXTILE FABRIC.

Application filed June 1, 1925. Serial No. 13,625. Term of patent 7 years.

To all whom it may concern:

Be it known that I, JAMES GOWANS, a subject of the King of Great Britain, residing at Leonia, in the county of Bergen and State of New Jersey, have invented a new, original, and ornamental Design for a Textile Fabric, of which the following is a specification, reference being had to the accompanying drawing, forming part thereof.

The drawing is a plan view of a textile fabric, showing my new design.

I claim:

The ornamental design for a textile fabric, as shown.

In testimony that I claim the foregoing as my invention, I have signed my name this 28 day of May, 1925.

JAMES GOWANS.
